[57] CLAIM

The ornamental design for a magnifying device for detail work, as shown and described.

DESCRIPTION

FIG. 1 is a side elevational view of a magnifying device for detail work showing our new design;

FIG. 2 is a side elevational view thereof showing the side opposite the side shown in FIG. 1;

FIG. 3 is a front elevational view thereof;

FIG. 4 is a rear elevational view thereof;

FIG. 5 is a bottom plan view thereof;

FIG. 6 is a top plan view thereof;

FIG. 7 is a sectional view taken along the line 7—7 of FIG. 6; and

FIG. 8 is a sectional view taken along the line 8—8 of FIG. 6.
